UNITED STATES PATENT OFFICE.

LOUIS MARX, OF NEW YORK, N. Y.

AMUSEMENT DEVICE.

Application filed December 26, 1924. Serial No. 758,094.

This invention relates to an amusement apparatus, and more particularly to an amusement apparatus of the type in which a vehicle platform or carrier is oscillated 5 with a rotary tilting or gyrating motion to cause one or more vehicles to travel thereon cyclically in circular paths.

Amusement apparatus in which a vehicle platform or carrier is oscillated with a rotary 10 tilting or gyrating motion have been constructed in a number of forms and utilized either as amusement railways or "roundabouts", or as racing toys. When constructed as an amusement railway or "round- 15 about", the platform or vehicle carrier is oscillated or is given a combined rotary and oscillatory motion to cause occupant-carrying vehicles or cars thereon to travel or be automatically propelled by gravity in circu- 20 lar or other orbits. When constructed as a toy, the platform or vehicle carrier is os- cillated to cause simulated vehicles such as railway cars, automobiles and the like to travel cyclically in circular or other paths 25 thereon. A principal object of the present invention relates to the provision of an im- proved and simplified gyrating amusement 30 apparatus of this type which may be embodied as an amusement or pleasure rail-

way or as a racing toy.

More specific prime objects of my invention include the provision of an amusement apparatus in which a novel and improved means is utilized for supporting the plat- 35 form for its gyrating motion to permit of securing a balanced, smooth and uniform rocking motion of the platform with rela- tively simple and easily operable motor mechanism; the further provision of an 40 amusement apparatus of this nature in which the motor mechanism for oscillating the platform or carrier embodies means for rockably supporting the platform; and the still further provision of an apparatus of 45 this nature in which the platform and motor mechanism therefor are associated or inter-related so as to permit the same to be readily assembled and disassembled by the user or operator to afford easy access to 50 the parts for purposes of adjustment, repair and replacement of parts, the organization being such that when the apparatus is con- 55 structed in the form of a racing toy, the parts may be boxed or packaged in disassembled formation by the manufacturer, such parts being readily put together by the

simple step of placing the platform in position on the motor mechanism without adjustment of any of the parts.

A further and correlated principal object 60 of my invention therefore consists in organizing and relating the platform, its support and the motor mechanism therefor in accordance with a simple law of combination so as to permit the manufacture of the 65 amusement apparatus, especially when embodied in the form of a toy, with the fewest of parts and at a comparatively low cost of production, assembly and distribution.

To the accomplishment of the foregoing 70 and such other objects as will hereinafter appear, my invention consists in the elements and their relation one to the other, as hereinafter particularly described and sought to be defined in the claims; refer- 75 ence being had to the accompanying drawings which show the preferred embodiment of my invention, and in which:

Fig. 1 is a vertical elevational view with parts broken away of the improved amuse- 80 ment apparatus embodying my invention, and

Fig. 2 is a plan view thereof.

Referring now more in detail to the drawings, the improved amusement device of my invention comprises the oscillatable vehicle carrier or platform generally designated as P which is supported and operated by a combined supporting and motor mechanism generally designated as M, the construction 85 being such that the operation of the motor mechanism imparts a rotary tilting or gyrating oscillating motion to the platform for causing one or more vehicles thereon to travel or be propelled in circular paths or orbits. 90

When the invention is embodied in the form of a toy, the platform P preferably comprises a plate or disk-shaped member 10 made of sheet material and stamped to pro- 95 vide a plurality of concentric annular ribs 11, 12 and 13 defining a plurality of annular or circular paths 14 and 15 forming raceways for one or a plurality of simulated vehicles or cars such as 16 and 17 which are adapted to travel or be propelled along the raceways 100 when the platform is given its undulating or oscillating motion. The platform is further provided with a central cup-shaped bearing 18 and with a slot 19 arranged in radial alignment with the bearing for cooperation 105 with the supporting means for the platform, which will be described presently.

As heretofore mentioned, one of the objects of the present invention centers about the provision of a novel and improved means for supporting the platform for its oscillating gyrating motion to permit of securing a balanced and smooth rocking motion of the platform with the use of relatively simple motor mechanism. To accomplish this end, the platform P is supported centrally by a vertical pivot post or standard 20, and preferably at the upper end 20' of said pivot post, the said end receiving the cup-shaped bearing 18 of the platform P and providing a pivot mounting therefor. Preferably the end 20' of the pivot post 20 is made pointed or conical-shaped, and the inner wall of the bearing 18 is also made conical so that a point pivot bearing between the post support and the platform is obtained. In the form of construction embodied in the drawings, the platform is constrained to an oscillating motion only and is restrained against rotation, and to this end there is provided an upwardly extending rod 21 fixed to a stationary part of the apparatus such as the lid or cover 22 of a motor casing 23, and the said rod projects through the slot or aperture 19 of the platform P . With this construction it will be seen that the platform is restrained against rotation and is supported in a balanced manner to permit of a free and smooth rocking or oscillating motion with the use of comparatively simple motor mechanism. It will be further apparent from the construction thus far described that the platform may be readily removed from its support by the mere lifting of the former from the latter, the parts being thus related and organized to permit the boxing or packaging of the parts in separated or disassembled formation in a compact manner and to permit the user to readily assemble the parts without the necessity of adjustment by simply placing the platform on its support.

In the preferred construction, for the purpose of still further simplifying the organization and reducing the number of parts to a minimum, the supporting post 20 forms part of the motor mechanism M . The motor mechanism M comprises a spring motor 24 housed by the casing 23, the said spring motor being provided with a winding means 25 for energizing the motor, and with a stop ratchet mechanism 26 for holding the motor in an energized condition, energization of said motor functioning for imparting motion to a train of gears connected to the pivot post 20 for imparting a rotating movement thereto. The gear train preferably comprises a gear 27 fixed to a drum 28 to which the spring motor 24 is attached, the gear 27 meshing with a pinion 29 fixed to a shaft 30, which shaft carries a gear 31, the said gear 31 meshing with a gear 32, which latter is fixed to the lower end of the pivot post or

shaft 20, the said shaft being journaled in spaced bearings 33 and 34 fixed to the casing 23.

Preferably the motor mechanism is provided with a starting and stopping device which comprises a gear 35 fixed to the shaft 30 and meshing with a pinion 36, to which is attached a toothed member such as a gear 37, both fixed to a shaft 38, the said toothed member cooperating with a crank portion 39 of a movable arm 40, the said arm being adapted to be rocked from the position shown in Fig. 1, in which the crank portion 39 is out of engagement with the teeth of the gear 37, to a position for causing engagement of said crank portion with the teeth of the gear 37, motion of the controlling arm 40 thus permitting the starting and stopping of the motor mechanism.

For imparting the desired oscillatory motion to the platform P , I provide means connected to the shaft 20 so as to be rotated thereby, the said means comprising in the preferred construction a member 41, which member includes a transversely arranged rod 42 adjustably receivable by the shaft 20 and fixed thereto by means of an adjusting screw 43, the said transverse rod carrying a rotary element or wheel 44 freely rotatable thereon, the said rotary element 44 being arranged for engaging the underwall of the platform and being adapted to ride in engagement therewith when the shaft 20 is rotated. With this construction, it will be evident that when the motor mechanism is released and the shaft 20 rotated, the rotary engagement of the wheel 44 with the platform P will cause all parts of the said platform to move progressively from high to low positions, so that the said platform is rocked with the angle of dip or inclination progressively rotating, the oscillating motion imparted to the platform being in the nature of a rocking or gyrating motion. As a result of this gyrating or rotary tilting motion of the platform, the vehicles 16 and 17 thereon in seeking the lowest levels will travel or be propelled along the raceways 14 and 15, and will thus move cyclically in annular paths or orbits in an amusing manner.

The manner of constructing and using my improved amusement apparatus will in the main be fully apparent from the above detailed description of the construction and operation thereof. It will be further apparent that by virtue of the balanced and pivoted mounting of the platform, the motor mechanism M may be of relatively simple construction, since the amount of energy required for oscillating the platform or vehicle carrier at its pivotal mounting is comparatively small. With the construction provided, therefore, I am enabled when the apparatus is embodied in the form of a

toy to employ comparatively inexpensive and simple motive mechanism and to obtain thereby an operation of relatively long duration. It will be further seen that the 5 means for effecting the oscillation of a platform is simple and composed of a minimum of parts, thus minimizing the possibility of derangement and wear and tear, and permitting the parts to be readily adjusted or 10 repaired by the child or operator. It will be further seen that by arranging the motor mechanism below the platform, a stable apparatus is obtained and the motor mechanism is appropriately concealed by the vehicle carrier. 15

It will also be seen that a further important advantage of the constructional embodiment of my invention resides in the relative arrangement provided, permitting 20 of quick assembly and disassembly, this facilitating not only its use by the operator, but the manufacture, assembling and packaging thereof by the producer as well as the distribution thereof in compact packages at 25 a low cost.

It will be apparent to those skilled in the art that numerous constructional changes may be made without departing from the principles of the invention. Thus although 30 in the preferred form of the invention the shaft 20 serves both as a supporting means and as a part of the motor mechanism, changes may obviously be made therein to permit these functions to be carried out by 35 independent instead of unitary means. Other and numerous changes may be made without departing from the essence of the invention, defined in the following claims.

I claim:

40 1. An amusement device comprising a motor casing, a motor mechanism housed by said casing, a rotary shaft connected to said motor mechanism and extending upwardly from said casing, a pivot bearing 45 concentric with and at the upper end of said shaft, an oscillatable platform mounted on and supported by said pivot bearing and a member fixed to said rotary shaft for movement therewith about the shaft as an 50 axis and arranged to engage said platform

in its rotation for oscillating the same with 55 a gyrating motion.

2. An amusement device comprising a 60 motor casing, a motor mechanism housed by said casing, a rotary shaft connected to said motor mechanism and extending upwardly 65 from said casing, a pivot bearing at the upper end of said shaft, an oscillatable platform having a central bearing mounted on the pivot bearing, the latter forming a support for the platform, the said platform being detachable from its support when lifted therefrom, and a member fixed to said 70 rotary shaft for movement therewith about the shaft as an axis and arranged to engage said platform in its rotation for oscillating 75 the same with a gyrating motion.

3. In an amusement device, a supporting 80 housing, a track structure comprising a dished plate associated therewith and having a support on the housing permitting of universal rocking motion, a cam eccentric to the point of support for the track structure and revoluble concentrically about the support for the track structure, in contact with a part of the track structure, the support and cam defining free upper points of support for the plate, the said free upper points of support being such that the plate is removable from the free points of support 85 by a lifting action, a motor operatively connected with the cam and a gravity propelled object on the track.

4. An amusement device comprising an 90 oscillatory platform, a post having a pivotal support for said platform, the said platform being removably attachable to said post, means adapted to be driven in a circle about the post and bearing against a part of the platform for imparting a gyrating motion to the platform about said pivotal support, said platform being also detachably receivable by said means, the said means and pivotal point of support being relatively 95 adjustable for varying the angle of gyratory movement of said platform.

Signed at New York city, in the county of New York and State of New York, this 23rd day of Dec., A. D. 1924.

LOUIS MARX.
